UNITED STATES PATENT OFFICE.

JOSEPH C. WHITEHOUSE, OF CINCINNATI, OHIO, ASSIGNOR TO WHITEHOUSE BROTHERS, OF CINCINNATI, OHIO, (A COPARTNERSHIP CONSISTING OF JOSEPH C. WHITEHOUSE AND WILLIAM H. WHITEHOUSE).

DESIGN FOR A RING.

52,014.

Specification for Design.

Patented May 7, 1918.

Application filed February 5, 1918. Serial No. 215,545. Term of patent 3½ years.

To all whom it may concern:

Be it known that I, JOSEPH C. WHITEHOUSE, a citizen of the United States, residing at Cincinnati, in the county of Hamilton and State of Ohio, have invented a new, original, and ornamental Design for a Ring, of which the following is a specification, reference being had to the accompanying drawing, forming part thereof.

The figure is a perspective view of a ring, showing my new design.

I claim:

The ornamental design for a ring, as shown.

JOSEPH C. WHITEHOUSE.
